UNITED STATES PATENT OFFICE

2,461,385

ARTICLE OF FURNITURE

Regina Katherine Logue, Philadelphia, Pa.

Application August 17, 1946, Serial No. 691,184

4 Claims. (Cl. 155—124)

1

This invention relates to a table and chair assembly of a folding nature, so designed as to be easily manipulated into a thin, flat, decorative unit, suitable for storage in closets; when it is so desired to dispose of these articles of furniture.

It is the object of this invention to provide a table whose legs are disposed of by means of folding into a recessed apron, and maintained therein in rigid fashion by means of spring clips, thus forming a neat, smooth, box-like package of the table for easy handling, the under side of this table to be provided with a plurality of spring clamps, so arranged as to maintain the collapsed chairs, specifically four in number, in a position flat with the under side of the table top, so compactly as to form a rigid, flat, rectangular package, narrow enough for the confines of the most shallow closets.

These objects and others, such as economical construction, strength and lightness of structure are accomplished by novel construction and arrangement of parts, whose description will follow.

In the accompanying drawings, Fig. 1 represents a perspective of the table and group of two chairs arranged for individual use; Fig. 2 represents a perspective of the table and chairs as folded for storage; Fig. 3 represents a side elevation of the assembly in folded condition showing the narrowness and compactness; Fig. 4 represents a perspective of the under side of the table showing the legs opened and the chair-retaining means; Fig. 5 represents a fragmentary sectional elevation showing the nested position of the chairs within the table; Fig. 6 represents a fragmentary perspective showing one form of spring clip retaining means for the table legs; and Fig. 7 represents an enlarged section of the rubber covered clamp construction.

Referring to the drawings, one form of the present invention comprises a table having a top 15, preferably of square configuration, having an apron 16 provided on the underside thereof and extending continuously in close proximity to the sides of the top 15. As shown, this apron 16 is an inwardly disposed continuation of the material of the top 15 and is shaped to form in plan a square recess 14 in which the legs 17 of the table are received when in folded condition. Thus, with the legs 17 within the recess 14, the outer faces of the legs 17 lie substantially in the same planes as the respective sides of the table top so that a flat, smooth-sided, compact, rigid package is the result. Toggle links 18 are interconnected

2

between the apron 16 and the respective legs 17 and serve the dual purpose of locking the legs in open position and snapping the legs into folded position. When so folded, spring clips 19 lock the legs in the recess 14, these clips 19 being attached to the apron at spaced suitable locations.

In order to support folded chairs under the top 15, pairs of spring clamps 20 are provided, two pairs being disposed at two opposite sides of the top, and two other pairs being disposed at opposite sides of a reinforcement brace 23, which extends medially and transversely across the under side of the top. This brace 23 thus forms two compartments, each of which will seat two folded chairs whereupon one pair of clamps 20 on the brace 23 and the other pair on the apron side will grip a chair in the compartment and hold it rigidly fast. Preferably, each clamp 20 is made of heavy gauge spring wire covered by a heavy casing 21 of rubber. Each clamp of a pair is welded or otherwise secured to a spring hinge 24 fixed to the apron 16 in one instance, and to the brace 23 in the other instance. These clamps 20 are so hinged as to swing downwardly and outwardly to provide clearance for placing the chairs in the respective compartments, and each is of sufficient length to well overlie the chairs when in the compartments, so that the pressure of the spring hinges plus the spring action of the clamps insures a forced, constant and rigid grip on the confined chairs. Preferably, also, each clamp of a pair is connected to the other by a rod 26, which serves as a convenient handle 35 for swinging the clamps from operative to inoperative position and vice versa.

The chairs, preferably four in number, comprise seats 27 arranged to be supported near the front by pivoted rearwardly inclined legs 28, preferably of strap metal which have pivotal connection with the respective rear legs 29. These latter extend upwardly above the seat 27 to provide a support and frame for the convex leather chair back 30, which slopes from top to bottom 45 to a point about two inches beyond the leg extension rails, thus assuring a proper pitch for the back support. Stops 31 attached to the seat frame serves to hold the back in supporting position.

It will now be apparent that a new and novel table and chair assembly has been devised wherein chairs can be readily collapsed and folded into a thin, flat position, easily inserted into the compartments respectively for engagement by the clamps 20 to be there held rigidly and compactly

out of the way, but readily removable for use when desired.

It is a feature of importance that the bias on the clamp 20 is such that after the chairs have been withdrawn for use, the clamps spring upwardly against the table top and are both invisible to the eye and are also out of the way of the knees of the table users when the table is set up for use.

Obviously, when housed, the chairs are held rigidly in a protected position with the table, which preserves the finish of the chairs, and the entire assembly is so compact as to fit readily into relatively shallow closets.

1. A table comprising a top, legs pivotally mounted for movement relative to said top, a recessed apron depending from said top spaced inwardly of the peripheral rim of the top, said apron defining with the top a chair receiving recess inwardly of the apron, and forming with the top outwardly of the apron a niche for housing said legs in folded condition, in combination with a plurality of collapsible chairs, a plurality of spring clamps attached to said apron and arranged to overlie said chairs when folded and positioned within said recess, and means mounting said clamps to swing outwardly from under said apron to permit said chairs to be positioned within and removed from said recess, said means mounting said clamps providing an arcuate movement of said clamps on both sides of said apron and biased so that said clamps swing inwardly and upwardly of the apron when the chairs are removed from said recess in order to effect leg clearance for users of the table, and complementary spring clamp means mounted centrally of the table to cooperate with said first clamp means in supporting chairs in said recess.

2. A table comprising a top, legs pivotally mounted for movement relative to said top, a recessed apron depending from said top for effectively housing said legs in folded condition, in combination with a plurality of collapsible chairs disposed in stacks, spring clamp means in transversely spaced complementary relation, one of which is mounted on said apron, each of said complementary clamp means being arranged to overlie a pair of stacked chairs from opposite sides and apply constant spring pressure thereto to hold the pair of stacked chairs against said top, one of said clamp means comprising a plurality of relatively spaced clamping devices pivotally mounted on the said apron and a handle common to and extending between said spaced clamping devices mounted on the apron for manually operating said plurality of clamps simultaneously, to lock or release said stacked chairs relative to said top.

3. A table comprising a top, legs pivotally mounted for movement relative to said top, a recessed apron depending from said top for housing said legs in folded condition, reinforcing means beneath said top forming two compartments in combination with a plurality of collapsible chairs arranged respectively in stacked pairs to seat in each of said compartments in said

stacked relation when collapsed, clamps pivoted to the apron and movably mounted on the reinforcing means respectively arranged to overlie said stacked chairs when folded and positioned within said compartments, and spring means operative respectively between said pivoted clamps and apron and between said movable clamps and reinforcing means for mounting said clamps to exert yielding pressure on both sides of a pair of stacked chairs in a compartment to hold them therein, said clamp means both being movable to insert said stacked chairs in said compartment, said apron mounted clamps having arcuate movement on both sides of the position at which stacked chairs are held in the compartments, and said spring means thereof exerting a bias thereon to move said clamps inwardly and upwardly of the apron to effect leg clearance for users of said table when chairs are removed from said compartment.

4. In combination a table having a top, an apron depending from said top generally normal thereto, and a median division extending between parallel sides of the apron dividing the top into two chair receiving recesses defined respectively, by the top the apron and the median division, folding legs associated with the top, and a plurality of folding chairs disposed in pairs in stacks for disposition in the respective compartments, the total thickness of a stack of chairs being appreciably greater than the depth of said compartments, a clamp device having a foot and pivoted to the edge of the apron and of such length as to dispose said foot for overlying contacting engagement with the outer surface of said stacked chairs, means for pivotally mounting said clamp on the apron for arcuate movement on both sides of a position in which said foot contacts said outer surface of said stacked chairs, means biasing said clamp inwardly of said apron so that when the stacked chairs are removed the foot thereof is disposed inwardly and upwardly of the edge of said apron to secure leg clearance for the users of the table, said clamp being movable against the bias outwardly of the apron to facilitate insertion and removal of the stacked chairs, and complementary movable resilient means on the median division having a portion overlying and engaging the stacked chairs transversely spaced from the pivoted clamp to hold said stack in said compartment.
